UNITED STATES PATENT OFFICE.

ALFRED R. BARRACKS, OF DECATUR, ILLINOIS, ASSIGNOR TO DECATUR UNION CHEMICAL COMPANY, OF DECATUR, ILLINOIS, A CORPORATION OF ILLINOIS.

TOILET-ARTICLE CONTAINER.

1,321,274.

Specification of Letters Patent.

Patented Nov. 11, 1919.

Application filed October 24, 1918. Serial No. 259,567.

To all whom it may concern:

Be it known that I, ALFRED R. BARRACKS, a citizen of the United States, residing at Decatur, in the county of Macon and State 5 of Illinois, have invented new and useful Improvements in Toilet-Article Containers, of which the following is a specification.

The present invention relates to receptacles of that type used for toilet articles, 10 such as small paste jars, powder boxes, and the like and has for its object to provide a kit or toilet case which may be cheaply constructed; which will be attractive in appearance; which will be of such make up as that 15 it will retain its shape and serviceability after continued use; which is of such construction as that, when opened, the contents are readily accessible for use or replenishment; and which may be shipped in flat or 20 knocked down condition from factory to distributor.

In the drawings herewith is illustrated one embodiment of the invention and that the best now known to us, and in said drawings:—

Figure 1 is a top plan view of the toilet case.

Fig. 2 is a side view of the case shown in Fig. 1.

Fig. 3 is a plan view of the blank from which the case is formed.

Fig. 4 is a perspective view showing the case open, toilet articles being indicated in dotted lines.

Figs. 5 and 6 are detail sectional views to show the wall supporting means.

Fig. 7 is a view similar to Fig. 3, showing a single piece blank.

In the drawings the same reference characters refer to like parts in the several views.

The receptacle will be formed of a substantially cruciform blank as, for example, the blank shown in Fig. 3, this blank comprising the body portion 10 having wings to form side flaps 11 and end flaps 12, as shown. The blank may be formed as shown in Fig. 3, in which construction the end flaps 12 are formed separately and stitched or 50 otherwise secured, as at 13, to the body portion 10, or they may be formed as shown in Fig. 7, of a single piece of material so cut as to give the proper size and disposition of end and side flaps.

The blank thus formed will be slotted or 55 perforated in the flap sections, to form strap receiving loops 14, as clearly indicated in Figs. 3 and 7, and the end flaps 11 will be provided with suitable fasteners, as, for example, the snap fasteners 15, the 60 stud members of which will be carried by one end flap 11 and the socket members will be mounted on the other end flap 11, as shown in Figs. 3, 4 and 7.

It will be observed that the loops 14 are 65 formed in the flaps adjacent the body portion 10, which section of the flaps when folded up, as shown in Figs. 1, 2 and 4, will form the side walls of the receptacle or kit. It is obvious that this blank being made of 70 thin flexible material, preferably leather, of equal thickness throughout, would not furnish rigid or self supporting side walls and it is necessary, therefore, to provide strengthening and wall retaining means. 75 This is accomplished by providing a strap or band of flexible material 16, said strap being, preferably, of the same material as the kit. The strap 16 encircles the receptacle or kit lengthwise, and is threaded 80 through the loops 14, struck out from those portions of the blank which are designed to form the vertical walls of the receptacle. The strap 16 will, preferably, although not necessarily, be secured at one end as at 17 85 to the side wall of the blank, and the free end, after being threaded through the loops, and bringing the walls to a set-up position, will be secured, by a suitable fastening means, as for example, the snap fastener 18, 90 to the opposite end of the strap. The said strap 16 will reinforce and hold up the flexible walls of the receptacle, so as to do away with the necessity of stitching or otherwise securing together the corners of the blank 95 formed by the meeting edges of the vertical or side walls and dispense with wall stiffening and strengthening means, so that the operations necessary to make up and complete the article are very simple and the 100 necessity for complicated stitching or fastening and stiffening operations for the corners and walls are entirely done away with.

The strap 16, when the receptacle is set 105 up, will effectively hold the receptacle in shape with the side walls snugly together and the flaps free to turn so as to open the

kit as shown in Fig. 4. It will be seen that the blank with attached strap may be made up and shipped in knocked-down condition to be set up by the distributor by simply 5 threading the strap through the loops or straps and fastening the end.

If it should be desired to make the straps adjustable so as to compensate for stretching after continued use, there may be provided 10 a plurality of stud members 19 as shown in Fig. 6, so that adjustment is provided for.

A kit constructed in accordance with this invention may be made of light stock and 15 quickly assembled and brought to its final form, for it will be seen that the formation of the blank of which the receptacle is made is a simple stamping operation; that the fastening devices may be readily applied; 20 and that the wall supporting or securing means, namely, the straps 16, can be very quickly and conveniently assembled so as to give a box-like structure with the free opening side and end flaps conveniently snapped 25 together and so disposed as that the contents of the receptacle can be readily procured.

It will be understood that variations in 30 construction which are within the range of mechanical skill may be made without departing from the spirit of my invention, the present disclosure being illustrative, but in no sense restrictive of the invention.

I claim:

1. A receptacle of the class described formed of a single substantially cruciform 35 blank to give a bottom, side and end walls, and cover flaps therefor; strap-receiving loops struck out of the wall sections adjacent the bottom section; a strap secured at one end to a wall section and having its free 40 end threaded through the loops in the wall sections, so as to encircle the receptacle and maintain the walls in upright position with the cover flaps folded over the top of the receptacle; and detachable means fastening 45 the free end of the strap to a wall section.

2. A receptacle of the class described formed of a single substantially cruciform blank to give a bottom, side and end walls, and cover flaps therefor; strap-receiving 50 loops struck out of the wall sections adjacent the bottom section; a strap secured at one end to a wall section and having its free end threaded through the loops in the wall sections, so as to encircle the receptacle and 55 maintain the walls in upright position with the cover flap folded over the top of the receptacle; and detachable and adjustable means fastening the free end of the strap to a wall section. 60

In testimony whereof I have hereunto set my hand.

ALFRED R. BARRACKS.
